UNITED STATES PATENT OFFICE.

WILLIAM HENRY CONE, OF BERLIN, ONTARIO, CANADA, ASSIGNOR TO
THE CONE GAS MACHINE CO., OF DETROIT, MICHIGAN, A CORPORA-
TION OF MICHIGAN.

GAS-GENERATOR.

No. 830,883.

Specification of Letters Patent.

Patented Sept. 11, 1906.

Application filed June 7, 1905. Serial No. 264,173.

To all whom it may concern:

Be it known that I, WILLIAM HENRY CONE, of the town of Berlin, in the county of Waterloo, in the Province of Ontario, Canada, have 5 invented certain new and useful Improvements in Gas-Generators, of which the following is a specification.

My invention relates to improvements in gas-producing generators; and the object of 10 the invention is to produce a fire-pot bottom which will hold the fuel up in the center, and so produce an equilibrium of heat in the side and center. To carry out this object, I have 15 constructed and arranged my fire-pot bottom in the generator, as hereinafter more particularly explained.

The drawing represents a sectional perspective view of a lower portion of my generator, showing my improvement.

20 A is the casing of my gas-generator, which is preferably cylindrical in form and is provided for the major portion of its height with a firebrick lining A', surrounding the fire-bed, and peep-holes A², so that the operator may 25 be able to see the condition of the fire-bed.

A³ is a ring forming the bottom of the fire-brick.

20 A⁴ is an internal casing forming the lower portion of the fire-bed—that is, the portion 30 in which the ash falls. The casing A⁴ is provided with an outwardly-extending flange A⁵, which is supported on an annular angle-iron ring A⁶. The flange A⁵ has an upwardly-extending portion next the casing and forms an 35 annular space around such casing and beneath the fire-brick. B represents a series of holes arranged in a circle and communicating with such annular space. The sizes of the 40 openings of the holes B are controlled by a ring C, having a series of holes C', which are designed to register or partly register with the holes B, or the ring may be moved to entirely close the holes B. The means of turning the ring C is a handle C², which is suitably 45 connected to the ring and extends out through a slot in the side of the casing. These openings are designed for a purpose which will hereinafter appear.

50 D is the stationary bottom of the fire-pot, which is conical in form and provided with a projecting central portion D', which is hollow and extends in the form of a conduit down below the conical bottom and laterally to the

55 casing, as shown at D², having connected thereto a suitable flange-pipe D³, provided with a damper D⁴.

D⁵ is a pipe or conduit leading from the annular space surrounding the ash-bed to the conduit D².

E is a conical grate, which surmounts the 60 bottom D and is provided with a handle E', by which such grate is shaken. It will be noticed that there is a space between the bottom of the internal casing A⁴ and the bottom edge of the grate to facilitate the discharge of 65 the ashes.

The top of the conduit D' is closed by means of a valve F, supported on a central stem F', having an eccentric end F², through which extends the laterally-extending stem 70 F³, operated by a handle F⁴. It will now be seen by means of the handle F⁴ the position of the valve F may be regulated, so as to allow of more or less of a draft through the center of the fire-bed, depending upon the condition of the bed as to incandescence.

By the form of my supporting-bottom for the fire-bed the center of the fire-bed is, I find, kept substantially level instead of subsid- 80 ing, as is usual in other forms of grates or fire-bed bottoms of which I am aware. I am also enabled, as hereinbefore described, to keep the bed of the fire level by means of the raised center of the bottom for the fire-bed and by changing the drafts of steam-laden 85 air from center to side, or vice versa. I am also enabled to produce an equilibrium of heat from center to side and prevent air-channels from forming in the body of the fuel at the side and the deterioration in the quality 90 of the gas produced.

What I claim as my invention is—

1. In a gas-generator, a fire-pot bottom of conical form extending from substantially the center downwardly to the edge and leaving an edge opening underneath the fire-pot and a correspondingly-formed shaking-grate superimposed on the bottom and provided with a suitable shaking-handle as and for the purpose specified.

2. In a gas-generator, a fire-pot bottom of conical form having a substantially cylindrical raised projection in the center, said projection having an opening therein and a valve for controlling said opening.

3. In a gas-generator, the combination

100

- with a fire-pot bottom having a raised projection and a central air passage-way extending therethrough, of a valve extending over the central projection and passage-way and 5 means for raising and lowering the valve as and for the purpose specified.
4. In a gas-generator, the combination with a fire-pot bottom having a raised projection and a central air passage-way extending therethrough, of a valve extending over the central projection and passage-way, a stem supporting such valve and extending downwardly through the passage-way and means for raising and lowering the stem as 15 and for the purpose specified.
5. In a gas-generator, the combination with a fire-pot bottom having a raised projection and a central air passage-way extending therethrough, of a valve extending over the central projection and passage-way, a stem supporting such valve and extending downwardly through the passage-way, and provided with an eccentrically-formed lower end and a rod extending therethrough and 20 provided with a handle outside the casing as and for the purpose specified.
6. The combination with the bottom of the fire-pot having a raised central portion and a vertical passage-way extending 30 through such central portion of a conduit leading from such passage-way laterally outside the casing, a valve to close the top of the passage-way, and means for raising and lowering the valve as and for the purpose specified. 35
7. In a gas-generator, the combination with the fire-pot and casing surrounding the bottom of the same, an annular chamber surrounding the casing and communicating therewith through holes in the casing, and 40 with a source of steam and air-supply, of a bottom for the fire-pot provided with a raised center and passage-way therethrough and communicating with the annular chamber.
- ber, a valve covering the top of the passage-way and conduit extending through the raised center and means for controlling the valve as and for the purpose specified. 45
8. In a gas-generator, the combination with the casing and fire-brick lining for the fire-pot, of a casing forming the lower portion of the fire-pot and having a series of holes arranged around the upper portion thereof and provided with an outwardly-extending flange forming beneath the fire-brick an annular chamber opposite the holes, a steam and air supply in communication with the annular chamber and a ring provided with a series of holes correspondingly formed and arranged to the holes of the casing, and means for circumferentially adjusting the ring as and for the purpose specified. 50
- 55
9. In a gas-generator, the combination with the casing and fire-brick lining for the fire-pot, of a casing forming the lower portion of the fire-pot and having a series of holes arranged around the upper portion thereof and provided with an outwardly-extending flange forming beneath the fire-brick an annular chamber opposite the holes, 60 a steam and air supply in communication with the annular chamber, a ring provided with a series of holes correspondingly formed and arranged to the holes in the casing, means for circumferentially adjusting the ring and a fire-pot bottom provided with a raised center and passage-way extending through the raised center and communicating with the annular chamber aforesaid, and a suitable valve located above the raised center and passage-way and means for controlling such valve as and for the purpose specified. 65
